No. 14,966 Apr. 22, 1884

UNITED STATES PATENT OFFICE.

ROBERT HAM, OF TROY, NEW YORK, ASSIGNOR TO THE STANDARD OIL STOVE COMPANY, OF SAME PLACE.

DESIGN FOR AN OIL-STOVE.

SPECIFICATION forming part of Design No. 14,966, dated April 22, 1884.

Application filed March 7, 1884. Term of patent 7 years.

To all whom it may concern:

Be it known that I, ROBERT HAM, of the city of Troy, county of Rensselaer, State of New York, have invented and produced a new and original Design for Oil-Stoves, of which the following is a specification.

My design relates to oil-stoves; and it consists in the configuration and ornamentation of the parts of the stove as they are shown in the annexed photograph, forming a part of this specification, and as it will be described hereinafter.

The parts of the stove are designated by letter-reference, and their configuration and ornamentation described as follows.

The letter A indicates the top of the stove, with rectilinear side edges a^1 , rounded corners a^2 , and which top overhangs the body part beneath it.

20 The letter B designates the body part, which also has rectilinear sides b^1 , and rounded corners b^2 , the latter where they unite with the rectilinear sides being tilted laterally, as indicated at b^3 , and at the front bounded by the 25 vertical fillet b^4 .

The letter M designates a compound molding at the base of the body part, said molding enlarging in lateral projection as it descends, and being composed of an upper member of filleted and fluted cyma m^1 , a middle member of beveled band molding, m^2 , and a bottom member of filleted ovolو molding, m^3 , said compound molding as thus produced being rounded at the corners to correspond incurve 30 to the corners of the body part. The legs L at the corners, and immediately beneath the compound molding in their downward and outward projection, are curved laterally to correspond with the rounded curve at the corners of the body part; and these legs have 35 plain exterior surfaces, and their feet resting

on the exteriorly-rounded-out corner-surfaces of the subbase.

The letter S designates the subbase, which is beveled downwardly and outwardly, having rounded corners, and being ornamented on its curtained edges by being curved inwardly and upwardly from the corners, and then curved downwardly, to form in each of its sides the central ornament, S^1 , between 45 said curves, and at the corners the feet F.

The letter D indicates the door, which is longer than wide, is made to have two mica panes or lights separated by a central vertical stile, the latter being ornamented with a 55 central intaglio line terminating in three radiately-arranged intaglio darts at each end. Between the two panes and the top of the door is a recessed panel. Upon the edge of the door there is a single intaglio line bordering the "name-panel" at the top, bottom, and sides of the door.

As thus described, there is produced, by the configuration and ornamentation of the parts shown and described, a design for an oil-stove, 65 which is distinctive in its character as such, taken as a whole, and which presents to the eye of the beholder a very pleasing effect.

Having thus illustrated and described my design, what I claim, and desire to secure by 70 Letters Patent, is—

The design for an oil-stove, having the configuration and ornamentation shown and described.

Signed at Troy, New York, this 5th day of 75 March, 1884, and in the presence of the two witnesses whose names are by them hereto written.

ROBERT HAM.

Witnesses:

ROBERT SCORER,
CHARLES S. BRINTNALL.
